US0D1028276S

(12) **United States Design Patent** (10) **Patent No.:** **US D1,028,276 S**
(45) **Date of Patent:** **** May 21, 2024**

(54) **CENTRIFUGE HOUSING**

(71) Applicant: **Thermo Electron LED GmbH**,
Langenselbold (DE)

(72) Inventors: **Roy Thompson**, Boston, MA (US);
Oliver Davidson, Oceanside, CA (US)

(73) Assignee: **THERMO ELECTRON LED GMBH**,
Langenselbold (DE)

(**) Term: **15 Years**

(21) Appl. No.: **29/820,062**

(22) Filed: **Dec. 20, 2021**

(51) LOC (14) Cl. **24-02**

(52) U.S. Cl.

USPC **D24/219**

(57) **CLAIM**

The ornamental design for a centrifuge housing, as shown and described.

DESCRIPTION

FIG. 1 is a top right front isometric view of a centrifuge housing of the present invention;

FIG. 2 is a top left rear isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines in the drawings depict portions of the centrifuge housing that form no part of the claim.

1 Claim, 7 Drawing Sheets
